3 SHEETS—SHEET 3.

UNITED STATES PATENT OFFICE.

FREDERIC I. S. HYNEK, OF CHICAGO, ILLINOIS.

PORTABLE SHOWER-BATH.

1,302,559.

Specification of Letters Patent.

Patented May 6, 1919.

Application filed September 16, 1918. Serial No. 254,276.

To all whom it may concern:

Be it known that I, FREDERIC I. S. HYNEK, a citizen of the United States, residing at Chicago, in the county of Cook and State of Illinois, have invented certain new and useful Improvements in Portable Shower-Baths, of which the following is a description.

My invention broadly belongs to the general class of shower baths. It has for its object the production of an extremely simple, economical and practical device which may be readily moved about from place to place, either indoors or out for the purpose stated.

An important object is to produce a bath of the kind described adapted for field use, that is for the use of soldiers, workmen, farmers and others who can readily make use of a portable device, but by reason of circumstances find it impossible to make use of one of the permanent built in apparatuses found in common use.

To this end, my invention consists in the novel construction, arrangement and combination of parts herein shown and described, and more particularly pointed out in the claims.

In the drawings, wherein like reference characters indicate like or corresponding parts,

Figure 1 is a central vertical section through a portable device, which for convenience I will call a portable bath-room;

Fig. 2 is a sectional view through a heating device designed for use in the bath;

Fig. 3 is a sectional view substantially on line 3—3 of Fig. 1;

Fig. 4 is a partial vertical plan and sectional view taken just in front of the pumping mechanism shown at the right hand in Fig. 3, and looking toward the right;

Fig. 5 is a fragmentary view showing the preferred form of providing means for permitting the curtains to overlap to securely close the curtained walls;

Fig. 6 is a sectional view of the lower end of the pump tube;

Fig. 7 is a plan view partially in section to show the construction;

Fig. 8 is a section on line 8—8 of Fig. 7; and

Fig. 9 is a partial elevation showing a slight modification in the heating apparatus.

In the drawings, 1—1 indicates suitable standards which support the bath-room. 2

is the bottom of the room, which is preferably water tight, and drains into a well 3. 4 is the front of the device provided with a step 5 by means of which the party taking 60 the bath steps over the wall 4 and into the part inclosed by the floor 2 and the walls secured thereto. 5' is a rear wall. 6—6 are suitable supports, preferably metal rods secured to the supports 1, or in any other preferred manner, and extending upward a sufficient height for the purpose desired. The rods or supports 6 carry upon the upper end a circular curtain supporting rod 7, 70 and at the bottom a similar rod 8. A curtain 9 of canvas or other suitable material is supported by and extends between the rings 7 and 8, being strung thereon by means of rings 10 or any other preferred means. This permits the curtain to slide upon the rings to open the device for the purpose of 75 cleaning or airing the same.

At the back of the device I have provided means for containing the liquid for the bath. 80 In the preferred construction there are two vessels side by side marked 11 and 12. One of these vessels, as 12, has a fire pot 13 for any preferred fuel arranged below it, and if necessary, a smoke or gas outlet 14. By this means the fluid or water in the vessel 12 85 may be warmed or heated as desired. 15 is a door by which admission may be had to the fire box 13, and 16 is a similar door opening into an ash pot 17. It will thus be seen that one vessel, for illustration as 11, may 90 contain cold water, while the other, as 12, may provide hot water, the two being mixed as desired by means of the piping connecting the two to the pump. 18 is a pipe arranged 95 to conduct the fluid from the cold water tank 11 to the chamber of the pump 19, while 20 is a similar pipe to conduct water from the hot water vessel 12. The pipe 18 is provided with a valve 21, and 20 is provided with a valve 22 by which the flow of water through the pipes may be controlled. The tube or pipe of the pump 23 is extended 100 downward into the well 3, and has secured at its end a suitable screen or filter material 24. A valve 25 in the pipe 23 gives control to the pump so that the fluid may be pumped either from the vessels 11 and 12, 105 or from the well 3 as desired.

A pipe 26 extends from the pump upward near the top of the room and thence 110 bent forward and downward, and is provided with a spray 27. An auxiliary spray

28 may be provided if desired, controlled by a valve 29. This spray is placed at any preferred point, preferably in a position to give a horizontal delivery, while the spray 5 27 is arranged to secure a vertical delivery. 30 is a removable floor board upon which the bather stands. 31 is a drain cock to the well 3. 32 is a valve in the pipe 26 by means of which the delivery through the spray 27 10 may be cut off, giving all of the delivery through spray 28. 33 are stay braces extending from the supports to the upper ring to prevent the collapse of the device.

As stated, it is desirable that the canvas 15 or fabric wall of the room should overlap so as to give privacy to the room and prevent the splashing of the water. I prefer to accomplish this by means of the substantially concentric sector rings, shown in Fig. 5, 20 numbered 34 and 35. One free end of the curtain is strung by means of wire rings 36 upon the support 34, while the other is supported by the rings 37 upon the support 35. This permits the free ends of the curtain to 25 overlap as indicated, giving for a considerable distance a double thickness of the material at that point.

It is sometimes desirable to secure a steam or vapor bath, and my device is well 30 adapted to that purpose. As shown in Figs. 7 and 8, a pipe 38 is connected near the top to the hot water chamber 12 and extends into the room. A valve 39 serves to 35 control the same, and the heat may be raised in the fire box to a point where vapor or steam is given off and its admission into the room controlled by means of the valve 39. In this form of device it is desirable of course to cover the room. I accomplish 40 this by extending a canvas or other suitable cover over the top as at 40, securing the same to the rings or top of the device in any preferred manner.

Fig. 9 shows a simple modification for 45 heating the water in the hot water tank. As here shown, the tank 12 has its bottom substantially in line with the bottom of the room, and a gasoline or other suitable burner 41 properly inclosed in the casing 50 42 serves to heat the water. A suitable receptacle for the heating medium, as at 43, may be carried by the receptacle 12 or in any other preferred manner, a pipe 44 leading from the fuel receptacle to the burner 55 41. From the casing 42 the excess heat from the burner may be conducted beneath the floor to the room by means of a pipe 45, discharging near the front thereof, or conducted upward as near the front as preferred.

The mode of operation is apparent. The bather standing within the room closes the entrance, and by manipulating valves 21 and 22, and operating the pump 19, delivers a 60 spray through either one or both of the

spraying devices 27 and 28 at the preferred temperature. A large amount of water is not necessary to secure satisfactory results by reason of the fact that the water is not wasted, but may be used again. Thus the 70 water as it falls upon the floor 2 drains into the well 3, and the bather, when a sufficient amount of fluid has been used in the initial process, may then close the valves 21 and 22 and open the valves 25. This permits 75 the pumping of the accumulated water in the well 3 through the filter material at the end of the tube 23 upward through the pipe 26 as desired. Thus the water may be used over as desired by the bather, serving to 80 rinse off the soap, etc. After the bath is concluded the valve 25 may be closed and the valve 20 to the pipe 18 opened, and a cold spray may conclude the operation. When the bath is completed the well 3 may 85 be drained by means of the cock 21.

If a vapor bath is desired, of course it is only necessary in a room having suitable covering 40 to close all the valves except the valve 39 in vapor pipe 38, which will 90 permit that operation.

The entire device is extremely simple, and as stated, is particularly designed and is extremely desirable for use in the field where the water is of a limited quantity, 95 and opportunities to take a bath in the usual way are limited. Thus, it is particularly adapted for the use of soldiers *en route*, or for farmers or mechanics, and all others where it is impossible or difficult to secure 100 the luxuries of a modern bath-room, and where it is desirable to secure the benefits of a bath in the best way available.

Having thus described my invention, it is obvious that various immaterial modifications may be made in the same without departing from the spirit of my invention; hence I do not wish to be understood as limiting myself to the exact form, construction, arrangement and combination of parts 110 herein shown and described or uses mentioned.

What I claim as new and desire to secure by Letters Patent is:—

1. In a device of the kind described, a 115 portable bath-room, a pair of liquid vessels in proximity thereto, means for heating the liquid in one of the vessels, in combination with a pump within the bath-room, pipes extending from the vessels to the pump, 120 valves controlling the passage of liquid through the pipes, a well provided at the bottom of the room, a piped extension from the pump to the well, and a valve for controlling the passage of liquid through the 125 latter pipe, whereby fluid may be drawn from the pair of liquid vessels or from the well at will.

2. In a device of the kind described, a 130 pair of liquid vessels and means for heating

the water in one of said vessels, and a well arranged below the level of the liquid vessels, in combination with a pump, pipe connections from the liquid vessels to the pump, 5 and valves controlling the same whereby fluid may be drawn from either of said vessels alone or from both at will, a pipe extending from the well to the pump provided with filtering means therein, and a 10 valve controlling the passage of fluid through said pipe, a pipe extending from the pump to a vertical showering device and between the pump and said vertical showering device provided with a horizontal showering device, a valve for closing the passage 15 to said horizontal showering device, and a

valve between the horizontal showering device and the vertical showering device, whereby fluid may be drawn from either one or both of the liquid vessels or from the well, being filtered in its passage, at will, and said fluid may be discharged either from the vertical showering device or from the horizontal showering device also at will. 20

In testimony whereof, I have hereunto 25 signed my name in the presence of two subscribing witnesses.

FREDERIC I. S. HYNEK.
